UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed December 20, 1924. Serial No. 757,157.

This invention aims to provide an improved separable fastener.

In the drawings, which illustrate a preferred embodiment of my invention:—

5 Fig. 1 is a front elevation of a portion of a placket showing the stud and socket in dotted lines;

Fig. 2 is a section on the line 2—2 of Fig. 1, being partly in elevation;

10 Fig. 3 is an elevation view of the socket in position upon a flexible carrying medium; and

Fig. 4 is an elevation view of the stud in position upon its carrying medium.

15 Referring to the drawings, I have shown a separable fastener for use in securing the edges of a placket or the like together, the socket being so constructed and secured to the fabric that it cannot be separated from the stud when lateral strain is exerted thereupon.

The stud, as illustrated, comprises a head 1, a neck 2, and a base portion 3, secured to the stud-carrying fabric 4 by stitches which 25 pass through the fabric and through sewing holes 5 in the base portion 3 of the stud, thereby securing the stud firmly in position adjacent one edge of the placket.

The socket is preferably relatively thin 30 and may be formed from any suitable material, but I prefer, as illustrated, to construct it from a single piece of wire so as to present a stud-receiving aperture 6 surrounded on three sides by three relatively large loops 35 7, 8 and 9 and on the fourth side by two relatively small loops or eyes 10 and 11 which are formed from the free ends of the wire and are located relatively close together. The socket is secured to its carrying fabric 40 12 by securing stitches sewn over the outer ends of the loops 7, 8 and 9 and between the eyes 10 and 11, as best illustrated in Fig. 3. The result of securing the eyes 10 and 11 firmly together is to provide a socket which will 45 expand and contract rather evenly upon all sides of the stud-receiving aperture 6, thereby preventing distortion of the socket.

Heretofore the large loops of a socket of similar construction, have usually been formed having symmetrical curves throughout their entire length and, while a socket of such a construction has given some satisfaction, it has been noted that the curved ends of some of the loops have crowded through

the loops so that in effect the stitches operated to cam the loops through them sufficiently to spread the neck-engaging portions of the socket or to weaken or destroy the stitches. This generally took place when strain was exerted in such a direction as to move the socket toward the edge of the placket or the like. The result therefore was to spread the neck-engaging portions of the socket and permit separation of the stud and socket by lateral strain or else to break the stitches. To overcome the difficulties set forth, I have provided a socket in which at least two of the loops are provided with straight portions adjacent their outer ends so that, when lateral strain is exerted upon the socket, the movement between the loops and the stitches will not operate to expand the neck-engaging portions of the socket or to break the stitches.

Referring now to Fig. 3, it will be seen 75 that I have provided straight portions 13 at the outer ends of the loops 7 and 9 and that the loop 8, which is adjacent the edge of the fabric 12, is continuously curved at its outer end. It will also be noted that the 80 stitches, securing the loops 7 and 9 to the fabric, pass over the straight portions 13 of the loops. Thus when the stud and socket are engaged and a lateral strain is exerted upon the stud and socket, in such directions as will 85 tend to urge the socket toward the edge of the fabric 12, the straight portions of the loops 7 and 9 merely move or slide relative to the stitches without placing undue strain upon them or without effecting any cam action between the loops and the securing threads. Thus the neck-engaging portions 90 14 of the socket are not affected by lateral strain exerted upon the socket and they only expand when the stud is being engaged with 95 or disengaged from the socket.

While I have illustrated and described a preferred embodiment of my invention, it will be understood that my invention is best defined in the following claims:

1. A relatively thin fastener socket presenting a stud-receiving aperture, a plurality of stitch-receiving loops spaced about said aperture, and stitched to a flexible support neck-engaging means for cooperating with the neck of a stud and stitch-receiving straight portions located at the outer ends of some of said loops to permit shifting of

- said loops relative to the carrying medium to which said socket is secured without effecting spreading of said neck-engaging portions or placing undue strain upon the stitches. 25
5. 2. A relatively thin fastener socket presenting a stud-receiving aperture, a plurality of resilient neck-engaging portions surrounding said aperture and a plurality of stitch-receiving loops stitched to a flexible 10 support, two of said loops presenting straight portions at their outer ends to permit movement of said loops relative to their cooperating securing stitches, when strain is exerted upon said socket in a direction toward the 15 edge of the support, thereby to prevent undue strain on the stitches.
3. A relatively thin one-piece socket presenting a stud-receiving aperture, a plurality of loops stitched to a flexible support and presenting, neck-engaging portions for engagement with the neck of a stud, two opposed loops presenting, at their outer ends, relatively straight portions parallel with the normal line of strain exerted upon the socket 20
- when secured to a stud, thereby said straight portions permitting movement of the loops relative to the stitches without placing undue strain on the stitches and without effecting expansion of the neck-engaging portions. 25
4. A fastener socket formed from a single piece of wire and presenting a stud-receiving aperture, a plurality of spaced apart resilient stud-engaging jaws surrounding said aperture, means for providing even distribution of the expansion of said jaws and a plurality of relatively large stitch-receiving loops spaced about said jaws, two of said loops transverse relative to the normal line of strain exerted upon the socket, said loops having straight portions at their outer ends parallel 30 to said line of strain to provide means whereby the loops may be shifted relative to the stitches without effecting expansion of said jaws. 35
- 40

In testimony whereof, I have signed my 45 name to this specification.

FRED S. CARR.
